(57) **CLAIM**

The ornamental design for a card edge connector, as shown and described.

DESCRIPTION

FIG. 1 is a front, top and right side perspective view of a card edge connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a partly enlarged view taken from the circle shown in FIG. 6 to illustrate the disclaim element thereof.

The broken line portion in FIGS. 6 and 7 drawing view is included to show unclaimed subject matter only and forms no part of the claimed design.
